ROCKABLE TANK TEXTILE WASHING MACHINE

Warren O. Manley, North Kansas City, Mo., assignor to C. Earl Hovey, trustee, Kansas City, Mo.

Application May 20, 1946, Serial No. 670,994

3 Claims. (Cl. 68—148)

1

This invention relates to laundry equipment and particularly to power driven washing machines and is a continuation in part of my co-pending application, Serial No. 562,754, filed November 10, 1944.

The primary aim of this invention is to provide a washing machine of the aforementioned character having as a part thereof unique means for supplying steam and water to the articles being washed as the rockable tank of the machine is actuated.

Further objects of this invention are to provide a washing machine having a rockable tank and means for driving the same that is equipped with specially formed end walls designed to direct the water in a figure 8 path of travel above a perforated false bottom through which steam may be introduced as the machine is functioning; that is provided with a pair of spray heads guarded by a portion of the tank wall and disposed to direct jets of water toward the ends of the tank to engage the articles being washed as they are driven through the aforesaid figure 8 path of travel and as they are dropping toward the bottom of the tank near the center thereof; and that is provided with means for draining the tank as power is being applied to the machine.

Other objects of the invention include a number of specific details permitting the tank of the washing machine to be constantly actuated as steam and/or water is applied thereto and as the tank is being drained.

Further aims of the invention will appear during the course of the following specification referring to the accompanying drawing, wherein:

Fig. 1 is a top plan view of a power driven washing machine made pursuant to the present invention and having parts thereof broken away for clearness of illustration; and

Fig. 2 is a side elevational view thereof with parts in section to reveal the precise structure of the machine.

The form of machine chosen for illustration comprises a frame generally designated by the numeral 10 and upon which is mounted a prime mover such as an electric motor 12. This motor is joined to an eccentric wheel 14 linked to tank 16 through the medium of member 18 pivotally connected as at 20 to eccentric wheel 14 and similarly as at 22 to tank 16 to one side of its axis of rotation upon aligned stub shafts 24. These stub shafts 24 are positioned near the bottom of tank 16 on the transverse longitudinal median line thereof and are in turn journaled in bearings 26 supported by frame 10. A speed reducer

28 likewise carried by frame 10 is joined to motor 12 by shaft 30 and interconnected with eccentric disc 14 by a belt 32 passing over suitable pulleys 34 and 36 forming a part of speed reducer 28 and eccentric 14 respectively.

Tank 16 has a false perforated bottom 38 below which a dished portion 40 of tank 16 is disposed and from which portion drain opening 42 extends. This drain opening 42 is in communication with a drain pipe 44 having a valve 46 therein and to permit the movement of tank 16 without disengaging the means for draining the same, a flexible section 48 is interposed between outlet opening 42 and pipe 44. False bottom 38 is substantially flat and has positioned thereon a pair of longitudinally disposed ribs 50 that are formed as shown in Fig. 1 to diverge as the ends of the tank are approached from the transverse median line thereof. In other words, ribs 50 are arched in the form of a flattened V with the points closer together than the ends of the ribs. Such formation insures the separation of the load of clothes being treated as they are thrown from the center of tank 16 toward the ends thereof in their normal path of travel as tank 16 is rocked about its axis of rotation.

The ends of tank 16 are rounded and substantially curved in shape with an open section facing inwardly and defined between the flat side walls 52 of tank 16, the false bottom 38 thereof and an inwardly and downwardly projected lip 54 that extends below the flat portion of the top wall 56 of tank 16. This flat top wall 56 combines with lips 54 in forming a cavity 58 near the top of the tank within each of which is positioned a transverse pipe 60 forming a spray head capable of directing jets of water through openings 62 in paths of travel shown in Fig. 2. These spray heads 60 are interconnected by a pipe 64 which in turn is joined to a valved pipe 66 extending to a source of water supply. A flexible section 68 permits unretarded rocking of tank 16 as water is allowed to enter the tank to impinge upon the articles being washed. An access opening 70 in top wall 56 has a closure 72 thereover and when this closure 72 is in the position illustrated in Fig. 2, the tank 16 is a completely closed receptacle. A door 74 at one end of tank 16 near false bottom 38 allows the removal of a load of washed articles when the tank 16 is inclined with one end thereof lower than the remaining portion. This door 74 controls an opening 76 formed in the arcuate end wall of tank 16. Door 74 is arcuate and concentric with the substantially annular end wall of

the tank and is swingably carried by a pair of arms 78 movable about aligned pivot pins 80 when pressure is exerted upon handle 82 on door 74. When such pressure is exerted, the door 74 will move upwardly as viewed in Fig. 2 and lie close to the arcuate end wall of tank 16 while opening 76 is being uncovered. Steam enters the chamber below false bottom 38 through a spray head 84 joined to a flexible section of tubing 86, which, in turn connects with steam pipe 88, valved as at 90.

In the operation of the machine, a rocking action about stub shafts 24 is established and the contents of tank 16 will follow a figure 8 path of travel to cause the articles being washed to drop with considerable force upon false bottom 38 and the overlying ribs 50. As the articles move toward the end of tank 16 after dropping at its center as just set forth, they will be spread apart through the action of ribs 50 and then cause to ride upwardly and inwardly along the arcuate surface of the end wall of tank 16 and the merging lip 54. This lip 54 protects spray heads 62 and when the articles being washed are to be rinsed, water is allowed to pass through spray head 62 and impinge upon the articles being washed as they are thrown downwardly and inwardly from the respective lips 54.

In many instances it is desirable to introduce steam into the charge of articles being washed and when such is the case, the steam is forced upwardly through perforated false bottom 38 and directly against the articles within tank 16. This action may be accomplished either as the tank is being rocked or when the same is in a stationary condition.

The draining of tank 16 is accomplished by opening valve 46 and it is oftentimes desirable to drain the tank at the same time fresh water is being directed thereinto through spray heads 62.

The employment of flexible sections 48, 68 and 86 allows the continuous operation of the machine without disconnecting the same from the source of steam or water supply or from the drain pipe 44.

Such advantages as arise from the structure just described are extremely advantageous in either home or commercial operation of the washing machine.

Having thus described the invention, what I claim as new and desire to secure by Letters Patent is:

1. A textile washing machine of the character described comprising a frame; a tank rockably carried by the frame, said tank having a top wall and a bottom wall merging at each end thereof into curved walls forming a pair of end walls and a portion of the top wall of said tank, said end walls each terminating in a lip projecting inwardly and downwardly into the tank; and spray heads in the tank disposed between other portions of the top wall of the tank and the lips respectively, said spray heads being arranged to direct fluid inwardly and towards opposite ends of the tank as the same is rocked on the frame.

2. A textile washing machine of the character

described comprising a frame; a tank rockably carried by the frame, said tank having a pair of spaced side walls, a top wall and a bottom wall merging at each end thereof into curved end walls, said end walls each terminating in a lip projecting inwardly and downwardly into the tank; and elongated spray heads in the tank extending between said side walls and disposed between the top wall of the tank and the lips respectively, said spray heads being arranged to direct fluid inwardly and towards opposite ends of the tank as the same is rocked on the frame, the axis of oscillation of the tank being at its bottom intermediate said curved ends thereof, whereby to alternately shift the textiles in the tank against said end walls and thence inwardly through the fluid emanating from the spray heads as the tank is rocked, said axis of oscillation being parallel to the longitudinal axis of said spray heads and on a plane substantially midway between the spray heads.

3. A textile washing machine of the character described comprising a frame; a tank rockably carried by the frame, said tank having a top wall and a bottom wall merging at each end thereof into curved end walls, said end walls each terminating in a lip projecting inwardly and downwardly into the tank; spray heads in the tank disposed between the top wall of the tank and the lips respectively, said spray heads being arranged to direct fluid inwardly and towards opposite ends of the tank as the same is rocked on the frame, the axis of oscillation of the tank being at its bottom intermediate said curved ends thereof, whereby to alternately shift the textiles in the tank against said end walls and thence inwardly through the fluid emanating from the spray heads as the tank is rocked; and a perforated false bottom in the tank having a pair of ribs on the uppermost face thereof, said ribs being formed to diverge as the ends of the tank are approached for spreading said textiles into said fluid emanating from the spray heads as the textiles are shifted toward said end walls.

WARREN O. MANLEY.
